UNITED STATES PATENT OFFICE.

JOHN W. CARLSON, OF SALT LAKE CITY, UTAH.

HOUSE-NUMBER.

1,077,801.

Specification of Letters Patent.

Patented Nov. 4, 1913.

Application filed February 10, 1912. Serial No. 676,699.

To all whom it may concern:

Be it known that I, JOHN W. CARLSON, a citizen of the United States, residing at Salt Lake City, in the county of Salt Lake 5 and State of Utah, have invented new and useful Improvements in House-Numbers, of which the following is a specification.

An object of the invention is to provide a house number that can be clearly distinguished in the day time and that can be 10 illuminated at night.

The house numbers now generally used to designate the location of a residence consist simply in metallic numerals which are 15 secured by screws or other securing members to the front of the house and which, although distinguishable in the day time from a distance, cannot be seen in the night season.

20 In my device I employ a number which when attached to a dwelling can be clearly distinguished in the day time and can be illuminated at night, the device being arranged so that if desirable, the numerals 25 can be interchanged.

In the further disclosure of the invention, reference is to be had to the accompanying drawings constituting a part of this specification, in which similar characters of reference 30 denote corresponding parts in all the views, and in which

Figure 1 is a perspective view of the device. Fig. 2 is a horizontal longitudinal sectional view taken on the line 2—2 in Fig. 35 1. Fig. 3 is a vertical transverse sectional view taken on the line 3—3 in Fig. 2. Fig. 4 is an enlarged fragmentary perspective view showing the locking member.

Referring more particularly to the views, 40 I provide a casing 10, preferably formed of sheet metal and tapered toward the rear, the front and bottom of the casing being open. The upper and lower sides 11, 12 of the casing 10 terminate at the front in 45 flanges 13, 14 adapted to form a track, the flange 13 being bent to extend upwardly and the flange 14 being bent to extend downwardly. An end 15 of the casing 10 projects forwardly beyond the flanges 13 and 50 14 to form a stop flange 16, the said stop flange being provided with an indentation 17 for a purpose that will be hereinafter more fully disclosed. An asbestos lining 18, 55 is secured to the rear side of the casing, within the same and the mentioned rear side of the casing is provided with a plu-

rality of openings 19 adapted to receive screws therethrough for securing the casing to the front of a dwelling, the asbestos lining 18 being adapted to prevent the radiation of heat to the material of the house and the said asbestos lining can be provided with a glazed surface, thus acting as a reflector. An electric socket 20 is secured to an end 21 of the casing and within the 60 casing wires 22, connected with the usual contact members of the socket, extend rearwardly to pass through an opening 23 formed in the rear of the casing 10, the socket 20 being adapted to receive a suitable incandescent lamp 24.

A slide 25 is preferably formed of sheet metal and consists of a frame having the upper and lower sides thereof bent rearwardly to form grooves 26, 27, adapted to 75 receive the flanges 13, 14 so that the slide can be slidably engaged with the casing 10. One end of the frame of the slide 25 is bent rearwardly to form a stop flange 28 adapted to limit the sliding movement of the slide 80 on the casing 10 and the other end of the slide 25 is open to slidably receive transparent panes, preferably formed of glass and having suitable numerals 30 formed thereon, 85 grooved spacing members 31 being mounted on the slide 25 and interposed between the panes 29 with the edges of adjacent panes extending into the grooves of the spacing members, thus spacing the numerals 30, as will be seen by referring to Fig. 1.

In the use of my device the casing 10 is secured to the front of the dwelling or other house, the electric wires 22 are connected with the socket 20 and the incandescent light 95 24 is then mounted in the socket in the usual manner, the electric wires being connected in the house through a suitable electric switch or the like. The transparent panes 29 are now arranged in the slide 25 as mentioned and the slide is then engaged 100 with the casing so that the flanges 13, 14 will be received in the grooves formed by the flanges 26, 27 of the slide 25. Now by exerting a pressure upon one end of the slide, the same will be slid inwardly until an end 105 of the slide abuts against the stop flange 16, the other stop flange 28 on the slide 25 being then adapted to abut against the other end of the casing 10, it being understood that the stop flange 16 not only limits the sliding movement of the slide 25 upon the casing 10, 110 but also prevents the transparent panes 29

from becoming dislocated on the slide and retains the panes in rigid position relatively to the slide. To further secure the slide to the casing 10, a bearing 32 is formed integral with the frame of the slide 25, at one end thereof and mounted thereon is a handled locking lever 33, preferably formed of an integral piece of wire having an end bent in a U-shaped form so that when the locking lever is moved into locked position, the extremity of the U-shaped portion of the lever will abut against the flange 13 of the casing 10, and the handled portion of the lever will depend adjacent the end 15 of the casing, thus locking the slide 25 to the casing 10 and preventing the same from being withdrawn from the casing until the locking lever is moved into unlocking position.

By providing an opening in the bottom of the casing the light within the casing, for illuminating the numbers on the panes 29 will also illuminate the porch or entrance to the dwelling, the number being usually placed to one side of the entrance to the dwelling and the mentioned opening will

also permit the heat produced by the incandescent lamp to pass outwardly therefrom and into the atmosphere.

I claim:

In a house number, the combination with 30 a casing having the front open, of flanges formed at the front ends of the top and bottom sides of the casing and constituting a track extending longitudinally of the casing, a stop flange formed at one end of the casing 35 by continuing the end of the casing beyond the front edge of the said track, a slide operable on the said track, number bearing panes supported in the said slide, a bearing formed by bending a portion of the 40 slide upon itself, and a handled locking member journaled in the said bearing and adapted for locking the said slide on the said casing.

In testimony whereof I affix my signature 45 in presence of two witnesses.

JOHN W. CARLSON.
